US0D1039951S

(12) **United States Design Patent** (10) **Patent No.:** **US D1,039,951 S**
(45) **Date of Patent:** **** Aug. 27, 2024**

(54) **BRACKET APPLIED TO A WINDOW TREATMENT**

2,031,698 A 2/1936 Fanzoi
2,108,939 A 2/1938 Lewis
D161,199 S 12/1950 Perelman

(Continued)

(71) Applicant: **Lutron Technology Company LLC**,
Coopersburg, PA (US)

(72) Inventors: **Mailing Ren Wu**, Lansdale, PA (US);
Margaret A. Block, Allentown, PA (US); **David A. Kirby**, Zionsville, PA (US); **Vladislav Pejic**, Allentown, PA (US)

(73) Assignee: **Lutron Technology Company LLC**,
Coopersburg, PA (US)

(**) Term: **15 Years**

(21) Appl. No.: **29/900,553**

(22) Filed: **Aug. 22, 2023**

Related U.S. Application Data

(63) Continuation of application No. 29/835,630, filed on Apr. 20, 2022, now Pat. No. Des. 1,000,256, which is a continuation of application No. 29/746,561, filed on Aug. 14, 2020, now Pat. No. Des. 953,148.

(57) **CLAIM**

The ornamental design for a bracket applied to a window treatment, as shown and described.

DESCRIPTION

FIG. 1 is a perspective view of a bracket applied to a window treatment showing our design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines illustrate structure or features which form no part of the claimed design.

1 Claim, 4 Drawing Sheets

US D1,039,951 S
